CLAIM

I claim the ornamental design for an energy storage system, as shown and described.

DESCRIPTION

FIG. 1 is a front view of the claimed design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a perspective view thereof; and,
FIG. 8 is a second front view thereof, with a cover removed.
The broken lines in the figures depict portions of the energy storage system which form no part of the claimed design.
